UNITED STATES PATENT OFFICE.

CHARLES ANTROBUS, OF THE UNITED STATES NAVY.

TURBINE.

No. 845,675.

Specification of Letters Patent.

Patented Feb. 26, 1907.

Application filed November 7, 1906. Serial No. 342,395.

To all whom it may concern:

Be it known that I, CHARLES ANTROBUS, a citizen of the United States, and serving in the United States Navy on board the U. S. S. 5 *Adams*, have invented certain new and useful Improvements in Turbines; and I do hereby declare the following to be a full, clear, and exact description of the invention, such as will enable others skilled in the art to which 10 it appertains to make and use the same.

This invention relates to improvements in parallel-flow turbines, and particularly to that class wherein reversal of the power-shaft is attained without changing the direction of 15 flow of the operating fluid.

In the instant case the primary object of the invention is to provide a revolvably-mounted outer shell member provided with inwardly-disposed radial vanes and an internal 20 rotary member provided with outwardly-disposed radial vanes, the vanes of the two members alternating longitudinally of the turbine, with means for throwing said rotary members in and out of clutch with the power-shaft and means for alternately locking and 25 releasing said members.

Another object of the invention resides in the particular construction and arrangement whereby the operating fluid is introduced 30 into the turbine.

While I do not limit myself to the exact details shown, for the purpose of disclosure reference is had to the accompanying drawings, illustrating a practical embodiment of 35 the invention, in which—

Figure 1 is a plan view of my improved turbine. Fig. 2 is an end elevation with the clutch members removed and the power-shaft shown in section. Fig. 3 is a longitudinal vertical section through Fig. 1, the view being broken away centrally. Fig. 4 is a transverse sectional view of the hollow head on the line 4-4 of Fig. 3 and looking to the left. Fig. 4^a is a fragmentary detail view on 40 the line x-x of Fig. 4. Fig. 5 is a side elevation of the clutch mechanism, showing the relative positions of the inner and outer clutches when the outer clutch is in operative engagement with the turbine. Fig. 6 is an 45 end view showing the manner of mounting the clutches so that they may slide longitudinally of each other. Fig. 7 is a side elevation of the clutch mechanism, showing the position of the clutches when the inner clutch 50 is in operative engagement with the turbine.

Fig. 8 is a detail view of one of the vanes or blades of the rotary members. Fig. 9 is a longitudinal sectional view through the outer casing and inner rotary member, showing a modified construction with the brake-bands 60 and other external parts omitted; and Fig. 10 is a local sectional view showing another manner of mounting the vanes.

1 designates the lower half of a plurality of bearings suitably mounted on a base-support, and 2 designates the upper half of said bearings bolted to the lower half, as shown in Fig. 2. These bearings are of circular construction and are adapted to receive and support a rotatably-mounted member 3, 70 comprising a shell forming an operating part of the turbine. While this shell is simply shown as being snugly mounted in the bearings, it will be understood, of course, that suitable roller or ball bearings may be interposed between the shell and the bearings 1 and 2. This shell 3 is provided at its ends with a reduced or hub portion 4, and for strengthening purposes this hub portion is connected to the shell by the strengthening webs 5, disposed around the heads of the shell. In order to have access to the interior of this shell, hand-holes 6 and 7, provided with suitable covers, are mounted at the respective ends of the shell or casing. 85

Extending longitudinally of the interior of the casing is an internal rotatable member, which in the drawings, Fig. 2, is shown as a substantially solid shaft 8, having a bore 9 therethrough terminating at one end in the 90 enlarged chamber 10. This internal member 8 is provided at each end with annular projections 11, operating in annular recesses formed on the inside of the heads 4 of the outer casing, and the insides of said hubs are 95 similarly provided with internal annular projections 12, operating in recesses cut in the member 8. This allows the rotary movement of these two members relatively to each other, but prevents longitudinal movement. 100 The hub portions of the outer casing are provided with suitable annular recesses to receive the glands 13 for forming a packing between the two rotating members. One of the hubs of the casing and the adjacent end of 105 the rotary member 8 are respectively provided with the annular clutch-teeth 14 and 15, adapted to co-operate with clutching mechanism, hereinafter referred to.

The shell or cylinder 3 is provided with a 110

longitudinal series of inwardly-extending radially-disposed vanes 16, terminating adjacent the internal rotary member 8, and said internal rotary member 8 is similarly provided with a longitudinal series of outwardly-extending radially-disposed vanes 17, the vanes of said members alternating with each other longitudinally of the turbine. One of these vanes is shown in Fig. 8 and comprises the curved blade 16, mounted on a base 18, which may be apertured for riveting or bolting the same to the cylinder or the internal rotary member, as the case may be.

At the inlet end of the turbine, Figs. 2 and 4, there is provided a suitable hollow head having nozzles or ports for introducing the operating fluid to the series of vanes. In the construction illustrated the internal rotary member 8 is provided with a plurality of radial passages 19, (four being shown,) and disposed around said passages is arranged a head or shell 20, having spaced walls forming the chamber 21 and provided on its front face with a plurality of nozzles or slots 22, disposed adjacent to and communicating with the vanes of the turbine at that end of the engine. The radial passage-ways 19 are in communication with the central bore of the internal member 8, which bore is provided with a pipe 23, extending through and beyond the other end of the engine and forming an inlet-pipe for the operating fluid. Within the enlarged chamber 10 and around the pipe 23 is disposed a suitable packing of asbestos or similar material 24, contained within a metal casing 25, which may be supported by braces 26, as shown in Fig. 3.

27 designates the exhaust or outlet pipe for the engine and is provided with a recessed flange 28, forming a bearing for the reduced end 29 of the inner rotary member 8, and interposed between this reduced end and the recessed flange referred to is a suitable packing-gland 30. The exhaust-pipe 27 is provided with brace-rods 31, which support a casing 24^a, containing asbestos packed around the pipe 23^a, forming a continuation of the inlet-pipe 23. The end of the pipe 23 is rotatably mounted within the end of the pipe 23^a, which latter pipe is provided with a suitable recessed flange to receive the packing-gland 32.

33, in dotted lines in Fig. 3, designates a hand-hole for getting access to said packing-ring.

34 designates the power-shaft, and slidably mounted thereon is a clutch member 35, locked against independent rotation relatively to said shaft by the longitudinal splines 36, Fig. 6, and slidably mounted on said inner-clutch 35 is an outer clutch member 37, similarly keyed to the inner clutch by means of the splines 36^a. The inner clutch is provided with an annular recess 35^a and the outer clutch with an annular recess 37^a, and

the faces of these clutch members are each provided with the teeth 35^b and 37^b, respectively, adapted to engage with the teeth 15 and 14 of the rotating members of the engine. These clutch members are simultaneously thrown into and out of engagement by means of the mechanism shown in Fig. 1, wherein 38 designates a lever pivotally mounted at 38^a and provided with a pin engaging the slot 35^a. The free end of this lever is connected with the operating-rod 39, pivotally connected, as at 40, to the pivotally-mounted handle 41. Similarly, the recess 37^a of the clutch 37 is in engagement with a pin on the pivoted lever 42, the free end of which is connected by the link 43 to one end of a pivotally-mounted arm 44, connected, as at 45, with the rod 39.

Any suitable means may be provided for maintaining either the outer cylinder 3 or internal rotary member 8 locked or released relatively to each other, and in the drawings I have shown (more clearly in Figs. 1 and 2) a friction-brake comprising two substantially semicircular segments 46, pivotally supported at their lower ends, as at 47, to the base-support and at their upper end provided with lugs 48, screw-threaded to receive a right and left handed screw, the outer end of which is rotatably supported in a suitable upright or bearing 49 and is provided with a hand-wheel 50. This brake may be disposed about centrally around the cylinder 3. For the inner rotary member I provide a similar braking-mechanism consisting of the pivoted segments 51 and the operating-screw 52, the outer end of which is mounted in the upright 53. The segmental brake-bands 51, preferably engage an enlarged annular shoulder 8^a, formed at the outer end of the internal rotary member 8, as clearly shown in Fig. 3. It will be understood, of course, that any suitable throttle arrangement may be provided for controlling the admission of the operating fluid.

From the foregoing it will be seen that in operation, the inner rotary member being braked and the outer rotary member released, with the teeth of the clutch member 37 in engagement with the teeth 14 of the outer rotary member, upon the admission of the operating fluid through the pipe 23, the same will pass through the radial passages 9 into the chamber 21, through the slots or nozzles 22, and striking the first series of vanes 16 will rotate the cylinder 3, and hence the power-shaft, in one direction, the operating fluid passing through the turbine and through a plurality of annularly-disposed slots 10^a, cut through the internal member 8, thence discharging into the outlet-passage 10, and finally through the exhaust-pipe 27. If it is desired to reverse the engine, the outer cylinder is locked, the inner member 8 released, and the clutch mechanism shifted, where- 130

upon the incoming operating fluid will force the vanes 17 and the internal member 8 in a reverse direction to that heretofore described, the passage of the operating fluid following 5 the same course as previously explained.

The hand-holes 6 and 7 afford easy access to the glands or stuffing-boxes 13 for repacking same when necessary. It will also be seen that by the link arrangement shown in 10 Fig. 1 that one of the clutch members will be thrown out of clutch as the other one is thrown in clutch.

Referring to Fig. 9, it will be seen that the principle and operation of the construction 15 is analogous to that previously described; but in a great many instances it has been found expedient to place the hollow head or shell centrally of the machine with nozzles on each side discharging to the vanes in opposite directions. In this construction, therefore, the inner rotating member 8 is provided at both ends with the enlarged chambers 10, 20 ports 10^x being provided at opposite ends of the turbine instead of at one end, as in the 25 previously-described structure. The passages 19 are disposed similarly to those previously described, but are located centrally of the turbine instead of at one end thereof, and over these passages is arranged the hollow 30 head or shell 20, carried by the inner member 8 and provided on its opposite faces with a plurality of circumferentially-disposed nozzles or ports 22 of the construction previously described, which nozzles discharge 35 the operating fluid to the vanes immediately adjacent thereto. It will be understood, of course, that the vanes on opposite sides of the hollow head will be so set as to properly receive the incoming operating fluid.

40 23 designates the inlet-pipe, as in the previous construction, and 10^x indicates a plurality of conduits extending through the central solid portion of the internal member adjacent the radial passages 19 and forming 45 communicating conduits between the two enlarged chambers 10, whereby the exhaust at both ends of the turbine may be conducted through the enlarged chamber 10 at the inlet end of the turbine and out through the exhaust-pipe 27.

In the modification shown in Fig. 10 it will be seen that the only difference between the structure therein shown and that previously described is that the heads 18^a of the vanes, 55 Fig. 8, are dovetailed into their respective supports, as at 18, Fig. 10.

Having thus described the invention, what I claim is—

1. In a turbine, the combination with an 60 inner rotary member provided with vanes, of an outer rotary member mounted on said inner member and comprising a casing provided with vanes, a power-shaft, clutch mechanism associated with said rotary members 65 and power-shaft, locking means for said mem-

bers whereby one member may be locked and the other free to rotate, and means for introducing the operating fluid through said inner rotary member to the vanes and thence through the latter and exhausting adjacent 70 the inlet end of the turbine, substantially as described.

2. In a turbine, the combination with a rotary inner member having a longitudinal bore therethrough and an enlarged recess 75 provided with a plurality of ports communicating with the exhaust end of the turbine and forming the exhaust-passage therefor, of a cylinder rotatably mounted on said inner member, said cylinder and inner rotary member being respectively provided with correlated vanes, an inlet-pipe extending interiorly of said inner member, means forming communicating passages between said inlet-pipe and the interior of the turbine, a power-shaft, clutch mechanism associated with said rotary members and power-shaft, and locking means for said members whereby one member may be locked and the other free to rotate, substantially as described. 80

3. In a turbine, the combination with a rotatably-mounted casing provided with vanes, of an internal rotary member provided with vanes and having an enlarged chamber and an inlet-pipe extending interiorly thereof, 95 said inlet-pipe terminating at radial passages through said inner member, and said enlarged chamber communicating with the interior of the casing through ports, a hollow head carried by said inner rotary member 100 in communication with said radial passages and provided on its inner face with a plurality of nozzles adjacent said vanes, annular clutch-gears carried by said casing and internal rotary member, a power-shaft, an inner 105 clutch member co-operating with said internal rotary member slidably mounted on said power-shaft but locked against independent rotation thereof, and an outer clutch member similarly mounted on said inner clutch member and co-operating with the clutch-gear of said rotating cylinder, means for simultaneously throwing said clutches in and out of clutch, and locking means for said rotating members whereby one member may 110 be locked and the other free to rotate, substantially as described. 115

4. In a turbine, the combination with a rotary inner member, of a cylinder rotatably mounted on said inner member, said cylinder 120 and inner rotary member being respectively provided with co-operating vanes, means located centrally within said cylinder adapted to discharge the operating fluid in opposite directions against the vanes therein, an inlet-pipe for introducing the operating fluid to 125 said internal discharging means, means for conducting off the exhaust, a power-shaft, clutch mechanism associated with said rotary members and power-shaft, and locking 130

means for said members, whereby one member may be locked and the other free to rotate, substantially as described.

5. In a turbine, the combination with a rotary inner member having enlarged chambers at opposite ends thereof and a central solid portion provided with radially-extending passages, communicating conduits being formed between said enlarged chambers adjacent said passages and one of said enlarged chambers communicating with the exhaust-pipe of the turbine, of a cylinder rotatably mounted on said inner member, said cylinder and inner rotary member being respectively 15 provided with coöperating vanes, communicating ports being disposed between said cylinder and enlarged chambers at opposite ends

of said series of vanes, an inlet-pipe passing through one of said enlarged chambers and communicating with said radial passageways, and a hollow head disposed around said radial passages and provided on its opposite faces with discharge-nozzles, a power-shaft, clutch mechanism associated with said rotary members and power-shaft, and locking means for said members, whereby one member may be locked and the other free to rotate, substantially as described. 20 25

In testimony whereof I affix my signature in presence of two witnesses.

CHARLES ANTROBUS.
